UNITED STATES PATENT OFFICE.

VEROL H. BYRD, OF WARRIOR, ALABAMA, ASSIGNOR OF ONE-HALF TO SOL BYRD, OF HICKORY, KENTUCKY.

INVALID'S BED.

1,274,851.

Specification of Letters Patent. Patented Aug. 6, 1918.

Application filed November 24, 1917. Serial No. 203,796.

To all whom it may concern:

Be it known that I, VEROL H. BYRD, a citizen of the United States, residing at Warrior, in the county of Jefferson and State of Alabama, have invented certain new and useful Improvements in Invalids' Beds, of which the following is a specification.

This invention relates to bedsteads employed in hospitals and similar institutions, and has for one of its objects to provide a device of this character whereby soiled bedding may be removed and clean bedding substituted therefor without disturbing the patient.

Another object of the invention is to provide a device which may be attached without material structural change to bedstead frames of various forms and construction.

When treating patients either in hospitals or like institutions or in the home, it is necessary to change the bedding at intervals, and this generally requires that the patient either be removed from the bed or otherwise disturbed or subjected to great inconvenience, frequently endangering the lives or retarding the recovery in critical cases.

The present invention comprises an attachment to bedsteads consisting of a plurality of sections arranged side by side, preferably transversely of the bedstead, and independently movable or depressible, whereby the portion of the mattress above the depressed section will be depressed to permit the removal of the bedding and re- placing it with clean bedding and without disturbing the patient.

Any required number of the movable sections may be employed and supported in any suitable manner, and it is not desired to limit the device in this respect. For the purpose of illustration five of the movable sections are shown, four mounted to swing laterally and one at the head end of the bedstead arranged to swing at the outer edge only.

In the drawings illustrative of the preferred embodiment of the invention—

Figure 1 is a side elevation partly in section.

Fig. 2 is a plan view partly in section. 50
Fig. 3 is a transverse section on the line 3—3 of Fig. 1.

Fig. 4 is a detail view, illustrating the manner of supporting the foot member of the device. 55

The preferred embodiment of the improved device includes an oblong supporting frame including side portions 10—11 of any suitable material.

For the purpose of illustration these side members are shown formed of L-bars and rectangular in outline. The "head" portion of the bedstead includes vertical tubular members 12 having dove-tailed sockets to receive tapered tongues 13, the latter rigidly coupled to the side frames 10—11 by brackets 15. The foot member of the bedstead includes vertical tubular members 16 and dove-tailed sockets 17, while the side members 10—11 are provided respectively with dove-tailed studs 18 rigidly coupled to bracket devices 19. By this means the side members 10—11 are detachably coupled to the head and foot members, and coact therewith to form the bedstead. 75

The side frames 10—11 are coupled at spaced intervals by transverse members 20 rigidly coupled to the side members by rivets or other suitable fastening devices. Mounted to swing at 21 between the vertical portions 12 of the head of the bedstead is a supporting section 22. The member 22 may be disposed in longitudinal alinement with the frame members 10 when in one position as shown in full lines in Figs. 1 and 2 or turned down at an angle between the members 12 as shown by dotted lines in Fig. 1, the object to be hereafter explained. 85

Disposed between the members 10—11 and also between the member 22 and the foot portion of the bedstead, are a plurality of supporting sections 23, the latter arranged side by side with their side edges spaced at slight distances, and are independently movable relative to the bedstead. Each of the sections 23 is provided with supporting means connected respectively thereto and to the transverse members 20. The support-

ing means shown for illustration consists of U-shaped bail devices 24 coupled at 25 to the sections 23 and pivotally connected at their free ends as shown at 26 to the members 20. By this means the sections 23 are mounted to swing vertically relatively to the frames 10-11. When the members 24 are in their upper positions the sections 23 will likewise be in their upper positions with 10 their upper faces adjacent to the upper lines of the members 10-11, and are free to swing into a lower position or with their upper faces spaced a considerable distance below the upper lines of the members 10-11, 15 the object to be hereafter explained.

Attached to certain of the members 20 are resilient holding devices coacting with the members 24 to support the latter and maintain the sections 23 in their upper position 20 against the ordinary pressure which may be applied thereto, but which will yield when abnormal pressure is applied to the sections 23 to permit the latter to be moved into their lower positions. When the sections 23 are moved into their upper positions the holding devices will automatically engage the members 24 and hold the sections 23 yieldably in their upper position. Each of the holding devices is formed of a 25 single section of wire bent substantially into U-shape whereby side portions 27 will be formed, and secured by staples or other fastening devices 28 to the members 20. Each of the sides 27 of the holding device is 30 formed with an inwardly directed stop or shoulder 29 to engage the vertically directed portions of the members 24. The shoulders 29 extend in angular direction relative to the engaged portion of the members 35 24 so that the members 27 will yield when abnormal pressure is applied to move the sections 23 into their downward position. The members 27 will be sufficiently rigid to prevent the downward movement of the sections 23 under the strains to which they 40 will be subjected when in use, but which will yield when lateral strain is applied, as will be obvious.

A suitable holding device is also applied 45 to the head portion of the bedstead to hold the member 22 yieldably in its horizontal position, as shown in full lines in Fig. 1. The holding device of the member 22 comprises a rod 30 of resilient material rigidly 50 secured at 31 to one of the standards 12 and provided with an intermediate offset 32 which engages above the shorter end of the member 22 adjacent to one of the pivots 21, and thus holds the member 22 yieldably 55 in horizontal position, the catch member 30-31 being of sufficient strength to hold the member 22 in horizontal position against ordinary strains, but which will yield when

abnormal strains are applied to move the member 22 into the position shown by 65 dotted lines in Fig. 1.

Sections of springs, indicated at 34, will be located upon each of the supports 23 and 22, and a section of a mattress indicated at 33 disposed upon each spring section. The 70 mattress sections are united by straps 35 to prevent them from displacement when the supports 22 and 23 and the springs thereon are lowered.

When soiled bedding is to be removed the 75 section 23 at the foot of the bed is depressed, or caused to swing into its lower position. This movement will release the portion of the mattress and spring above the depressed section. This also releases a portion of the 80 bedding which is folded into a flat roll beneath the feet of the patient, the next section 23 and the spring and mattress supported thereby is then depressed and the bedding further rolled over this latter section and the previously lowered section 23 returned to its upper position, and the third section 23 is then depressed and the released bedding further rolled beneath the patient 85 and above the third section 23 and the section 23 returned to its upper position, and so on until the soiled bedding has 90 been rolled upon the section of the mattress above the section 23 nearest the head. The head section 22 and its spring and mattress sections are then depressed and the bedding finally rolled into the depression 95 formed thereby and removed by withdrawing it laterally. The various steps of the 100 operation can be performed without disturbing the patient. The clean bedding is then folded into a flat roll and disposed beneath the patient in the reverse order.

By this means the soiled bedding may be 105 expeditiously removed from beneath the patient and replaced by fresh or clean bedding without seriously disturbing or inconveniencing the patient.

The improved device will also be found very convenient for enabling wounds in 110 various portions of the body to be dressed without disturbing the patient by simply depressing the member 23 which for the time being is located beneath the portion of the patient which is to be treated. Thus 115 the portion of the mattress immediately beneath the affected part of the patient is depressed leaving the body free for the operation of the surgeon or nurse.

Having thus described the invention, what 120 is claimed as new is:

1. The combination with a support, of a plurality of bedding carrying members, means for coupling one of the terminal bedding carrying members at its outer end to 125 swing downwardly at its inner end, and

means for supporting the remaining bedding carrying members for vertical movement.

2. The combination with a bedstead, of a plurality of bedding supporting members arranged side by side transversely of the bedstead, means for coupling one of the

terminal bedding supporting members at its outer end to swing downwardly at its inner end, and means for supporting the remaining bedding supporting members for vertical and lateral movement. 10

In testimony whereof I affix my signature.

VEROL H. BYRD. [L.s.]
